POTENTIOMETER CONSTRUCTION

Herbert M. Schendel, Santa Ana, Calif., assignor, by
mesne assignments, to Beckman Instruments, Inc.,
Fullerton, Calif., a corporation of California

Application March 11, 1957, Serial No. 645,081

13 Claims. (Cl. 338—143)

My invention relates to constructions for potentiometers and the like. More specifically, it relates to a retainer or positioning device for holding or spacing the turns of a multi-turn winding.

A problem often encountered in the electrical arts is the arcuate positioning of such turns relative to each other and relative to a housing. A typical example is the positioning of a multi-turn resistive winding in a housing to be contacted by a movable wiper, as in the art of making multi-turn potentiometers, resistors, delay lines, etc. While applicable to any multi-turn environment, the invention will be particularly exemplified with reference to multi-turn or helical potentiometers.

It is an important object of the invention to provide an improved structure for accurately positioning the turns of a multi-turn winding. A further object is to provide a simple and inexpensive positioning structure of this character comprising a tubing corrugated in the desired pattern of the multi-turn winding. Other objects lie in the novel association of such a positioning structure with a housing; also in the constructional features of the positioning structure and the manner or method by which it is associated with the winding or the housing.

According to the preferred practice of the invention, a thin-walled tube is first corrugated in the desired pattern of the winding, the winding being then positioned therein, the whole being then positioned in a tubular housing. In the potentiometer art, for example, the multi-turn resistance element will present an inwardly-exposed helical surface along which a suitably guided contact may move. In this or similar environments, the invention provides for accurate placing or spacing of the turns. It allows the winding to be closer to the housing than is the case with conventional constructions and permits the use of thin-walled housings resulting in greater compactness. Metal housings are particularly desirable from the standpoint of durability, shielding, compactness, and dissipation and equalization of heat.

In addition, for any given outside diameter of the potentiometer, the multi-turn resistance coil can have a larger diameter and thereby improve resolution and linearity. This becomes a striking advantage in the so-called miniature size potentiometers now in demand for missile guidance, transistorized circuits and other miniature or sub-miniature control systems employing multi-turn transducers or control devices made in accordance with the invention.

The drawing illustrates preferred embodiments of the invention and will suggest variations within the scope of the invention. Referring to the drawing:

Fig. 1 is a longitudinal cross-sectional view of a miniature potentiometer embodying some of the features of the invention;

Fig. 2 is a transverse fragmentary view taken along the line 2—2 of Fig. 1;

Fig. 3 is an enlarged fragmentary view of a single turn of the device; and

Fig. 4 is a similar fragmentary view of an alternative construction.

6 Referring particularly to Fig. 1, the potentiometer is shown as including a thin-walled tubular housing 10 having a cylindrical interior surface 11. While this housing can be made of any suitable material, distinct advantages arise from the use of a metal in those instances 10 where compactness, increased heat dissipation or improved isothermal conditions are desired. The ends of the housing 10 are suitably closed, as by end members 12 and 13. Pins 14 exemplify merely one way of holding the end members 12 and 13 in place.

15 Within the housing 10 is a winding-positioning element shown as comprising a tube 16 corrugated in a helical pattern. In this embodiment, the tube 16 is made of thin metal, the corrugations being produced by external or internal pressure respectively applied while the 20 tube is over a male die or in a female die. The resulting corrugated tube 16 will have an outer surface 17 providing a multi-turn helical crest 18 and an outwardly-facing helical trough 19. It will also provide an inner surface 20 with a similar multi-turn helical crest 21 and an inwardly-facing helical trough 22. These troughs and crests are formed by the corrugations of the tube 16.

It is preferred that the helical crest 18 be in engagement with the interior surface 11 of the housing 10. A 25 frictional contact in the zone of engagement will often suffice but supplementary attachment means can be used. In this latter instance, an intervening adhesive can be employed or the end turns of the crest can be pinned, soldered or welded to the housing 11. Alternatively or in addition, the ends of the tube 16 may pressurally engage shoulders 23 and 24 of the end members 12 and 13. A washer 25 is shown between the shoulder 24 and the lower end of the tube 16. The thickness of this washer will determine the longitudinal pressure applied to the 30 tube 16. Usually only sufficient pressure is applied to prevent longitudinal movement of the tube 16 but it will be apparent that increased longitudinal pressure can be employed to expand the corrugations against the cylindrical interior surface 11 of the housing 10. The invention 35 comprehends any suitable means for applying such longitudinal pressure to cause minute expansion of the tube 16 to clamp it within the housing.

The inwardly-facing helical trough 22 forms a multi-turn winding-receiving trough or space facing toward the 40 common axis of the tube 16 and the housing 10. A multi-turn winding 30 is disposed in this trough and will be positioned or shaped thereby to conform to the predetermined multi-turn pattern of the trough. This is a distinctly advantageous feature of the present invention because a trough of predetermined pattern can be formed in the tube 16, after which a winding of normally different pattern can be inserted, the ultimate pattern of the winding conforming to the pattern of the trough. By 45 normally different pattern I have reference to a deviation in spacing or size of the turns. For example, it is the usual practice to produce the winding 30 of a helical form slightly larger than the trough 22 so that it tends to expand therein upon release from the initial contraction necessary to dispose it in the trough. The winding 50 can be retained in the trough by friction or by cementing it therein. The preferred practice is to pin or weld one end of the core of the winding relative to the tube 16 and then exert an unwinding pressure on the other end to expand the winding before this other end is 55 similarly attached to the tube 16.

The winding 30 illustrated in Figs. 1, 2 and 3 is composed of a multi-turn core 32, typically insulated copper

wire, with a resistance wire 33 wound therearound in contacting or spaced turns. The preferred practice is to employ a cover 34 of insulation material over the winding so that this cover will hold the resistance wire in place and will electrically insulate the wire 33 from the tube 16 if the latter is formed of metal and the resistance wire is a bare wire. The cover 34 is removed in an inwardly-facing zone 35 of the winding 30 to present an inwardly-exposed helical surface engageable by the guided contact to be described. It should be clear, however, that coreless windings 30 can be employed or that other means can be employed for insulating the resistance wire from the tube 16. In addition, the tube 16 need not be formed of metal and if made of insulating material the wire 35 may come into direct contact therewith. In this latter connection, it is sometimes desirable to make the tube 16 of molded plastic material or other material of relatively high electrical resistivity.

Any suitable contact means can be employed to advance along the helical multi-turn winding 30 while being guided in a helical path or to advance from turn to turn of the winding 30 while being moved longitudinally of the housing 10. Figs. 1 and 2 illustrate guidance of a contact along the winding 30. As therein diagrammatically shown, a rotor 40 carries stub shafts 41 and 42 respectively journaled in the end members 12 and 13 to turn about the common longitudinal axis of the tube 16 and housing 10. The rotor 40 provides a longitudinal groove 44 along which a slider or block 45 may freely advance. This block carries a looped contact member 46 terminating in a contact 47 adapted to engage the zone 35 of the winding 30.

Means is provided to guide the block 45 from the tube 16 so that the contact 47 follows the convolutions of the winding 30. In this respect, the block 45 is shown as including a pair of flanges 49 extending loosely into the V-shaped space between each turn of the winding 30 and the adjacent wall of the trough 22. As the rotor 40 turns, the flanges 49 follow this space and advance the block 45 along the groove 44. Guidance of such a block by flanges extending into a space defined by adjacent turns is disclosed in the earlier patent to Beckman No. 2,454,986 and while the present invention can employ such a system it is preferred to effect guidance by a space formed in part by one turn of the winding and in part by an adjacent wall of a trough of a member which positions the winding, e.g. the corrugated tube 16.

Terminals connected by leads to the ends of the winding 30 may be of conventional form, being shown diagrammatically in Fig. 1 as including terminal tabs 52 extending through the end members 12 and 13. The contact 47 can be similarly connected by a conventional pigtail lead to a corresponding terminal member, not shown.

If intermediate taps are to be employed, the leads therefor may extend through aligned openings 53 and 54 in the tube 16 and the housing 10 respectively. If, as shown, the opening 53 lies along a crest 18, a tap wire 55 can be welded to the exposed winding and extend directly to the exterior of the housing 10. In other instances, a tap lead 56 can be connected to the winding through an opening 57 positioned remotely from the housing opening 54. In this instance, such a lead 56 may extend between an adjacent crest 18 and the housing 10 or may extend peripherally of the tube 16 to the opening 54 through a helical passage 58 formed by the trough 19 and the housing 10. This latter procedure has particular advantages when it is desired that tap connections or terminals are to be on or at either or both of the end members 12 or 13. When tap or terminal leads extend along the helical passage 58 they are automatically electrostatically shielded from the resistance element and from external fields. The helical passage

58 is of sufficient size to receive several small leads if desired. Some of such leads may run in opposite directions along the passage 58 and may be brought out either at the front or rear of the potentiometer or both. A tap lead extending along the helical passage 58 and from the end member 12 is indicated in Fig. 1 by the numeral 59.

It is preferable first to insert the winding 30 in the tube 16 and then position the resulting unit in the housing 10. This is particularly true when taps are to be connected to the winding 30. However, it is also within the scope of the invention to position the tube 16 in the housing 10 and then introduce the winding 30 into the tube.

In the preferred practice of the invention, both the tube 16 and the housing 10 are formed of thin metal. The resulting structure has excellent heat dissipation properties and enjoys the other advantages previously mentioned. It is within the scope of the invention to provide tubular fittings 60 and 61 through one or both end members 12 and 13 to provide for the ingress or egress of a heat-exchange fluid acting as a coolant or heat-regulating fluid. Such a fluid may freely circulate through the helical passage 58, being guided thereby to flow adjacent all portions of the winding 30 and in excellent heat transfer relation thereto.

It is sometimes desirable to insulate the tube 16 from the housing 10 or to further insulate the winding 30 therefrom. Fig. 4 illustrates a thin metal corrugated tube 64 coated on both sides with layers 65 and 66 of electrical insulating material. The tube 64 can thus serve as an electrostatic shield irrespective of whether the housing 10 is made of metal. Additionally, the resistance wire 33 can be a bare wire space-wound on a core 32 of insulating material or around a core space, reliance being placed upon the layer 66 to electrically insulate the corrugated tube 64 from the resistance wire.

Various changes may be made without departing from the spirit of the invention as defined in the appended claims.

I claim as my invention:

1. A multi-turn helical potentiometer including in combination: a tubular element corrugated in a multi-turn helical pattern, said tubular element having an inner surface with a multi-turn helical winding-receiving trough provided by the corrugations; a multi-turn resistance winding disposed in said trough and positioned thereby as a multi-turn helical winding of a pattern determined by said trough, said helical winding bounding a rotor space and presenting an exposed helical zone facing the longitudinal axis of said tubular element; a rotor; means for journaling said rotor to turn in said rotor space about said axis; a contact turning with said rotor; and means for guiding said contact to advance along said exposed helical zone in contact with the resistance winding and follow the turns thereof as said rotor is turned about said axis.

2. A potentiometer as defined in claim 1 in which the depth of said winding-receiving trough is no more than about half the diameter of the individual turn of said multi-turn resistance winding disposed therein measured in a plane including said axis to expose at least about half of such turn to said rotor space.

3. A potentiometer as defined in claim 1 in which each turn of said winding provides a V-shaped space with an adjacent surface of the trough, and in which said means for guiding said contact includes a flange extending loosely into said V-shaped space and mechanically connected to said contact to move same therewith.

4. A potentiometer as defined in claim 1 in which said corrugations extend less than the full length of said tubular element, leaving cylindrical non-corrugated end sections at each end of the tubular element, the trough being continuous and free of blockage between said end sections.

5. A potentiometer as defined in claim 1 in which said tubular element is a thin metal tube and in which said multi-turn winding comprises a multi-turn core wound with resistance wire surrounding said core in helical turns, said wire being coated with electrical insulation material engaging said metal tube.

6. A multi-turn helical potentiometer including in combination: a housing having a cylindrical inner surface; a tubular element in said housing corrugated in a multi-turn helical pattern and providing outer and inner surfaces each having a multi-turn helical crest and a helical trough formed by the corrugations, the helical crest of said outer surface engaging said cylindrical inner surface of said housing, the helical trough of such outer surface cooperating with said cylindrical interior surface to form a helical passage, the helical trough of said inner surface forming a multi-turn winding-receiving space formed by the corrugations and facing toward the longitudinal axis of said housing; a multi-turn resistance winding disposed in said winding-receiving space and shaped thereby into a multi-turn helical winding of a pattern determined by said corrugations, said helical winding bounding a rotor space and presenting an exposed helical contact zone facing said longitudinal axis; a rotor; means for journaling said rotor to turn in said rotor space about said axis; a contact turning with said rotor; and means for guiding said contact to advance along and in contact with said exposed helical contact zone of the resistance winding as said rotor is turned about said axis.

7. A potentiometer as defined in claim 6 in which said means for journaling said rotor includes end members closing the ends of said housing, a shaft to which said rotor is connected, and bearing means carried by at least one of said end members providing a bearing means for said shaft.

8. A potentiometer as defined in claim 7 in which said corrugated tubular element is disposed between said end members and has end surfaces receiving pressure therefrom in the direction of said longitudinal axis, and including means for attaching one of said end members 40 to said housing while applying sufficient longitudinal force

to said tubular member to compress it and expand laterally the helical crest of said outer surface thereof into pressural contact with said cylindrical inner surface of said housing.

5. A potentiometer as defined in claim 6 including a lead connected to said winding and extending along said helical passage formed by the housing and the helical trough of said outer surface of said tubular element.

10. A potentiometer as defined in claim 9 including end members closing the ends of said housing and cooperating therewith in providing an enclosing structure, said enclosing structure including an opening, and a conductor traversing said opening and electrically connected to said lead.

15. A potentiometer as defined in claim 6 in which said housing and the helical crest of said outer surface of said tubular element provide registering openings, and including a conductor traversing said registering openings and electrically connected to said winding at a position intermediate its ends.

20. A potentiometer as defined in claim 6 including ingress and egress means communicating with said helical passage at positions spaced from each other along the length of such passage for circulating a heat-transfer fluid along said passage between such positions.

25. A potentiometer as defined in claim 12 including an end member closing one end of said housing, and in which at least one of said ingress and egress means includes a tubular connection member for said heat-transfer fluid, said tubular connection member being carried by said end member.
